UNITED STATES PATENT OFFICE.

HARRY A. WRIGHT, OF SPRINGFIELD, MASSACHUSETTS, ASSIGNOR TO THE AMERICAN HARDWARE CORPORATION, OF NEW BRITAIN, CONNECTICUT, A CORPORATION OF CONNECTICUT.

VALVE-GRINDER.

1,341,001.

Specification of Letters Patent. Patented May 25, 1920.

Application filed March 20, 1919. Serial No. 283,845.

To all whom it may concern:

Be it known that I, HARRY A. WRIGHT, a citizen of the United States of America, residing at Springfield, in the county of 5 Hampden and State of Massachusetts, have invented certain new and useful Improvements in Valve-Grinders, of which the following is a specification.

This invention relates to improvements in 10 valve grinders and more particularly to a valve grinding apparatus, which is adapted to be secured to the cylinder block of an engine and to simultaneously effect the grinding of a plurality of valves.

According to one feature of this invention, 15 the valve-oscillating elements are mounted in a frame which has legs at its ends to support it from the cylinder block in overlying relation with the valves, and this frame is pivotally connected to a bar, 20 which is adapted for attachment to the cylinder block by the same means which hold the cylinder head thereto.

According to another feature of the invention, 25 the valve-oscillating elements are arranged for simultaneous oscillation by means including a manually operable lever, which lever is movable in a plane parallel with said frame, and so disposed as to afford, 30 not only a convenient means for oscillating the valves, but also a convenient means for raising or lowering the frame on its pivot.

Other features and advantages for the invention will appear in the following description and in the illustrative embodiment 35 of the invention in the accompanying drawings, in which—

Figure 1 is a top plan view showing a 40 valve grinder, embodying the invention, in place on the cylinder block of an engine;

Fig. 2 is a fragmentary side elevational view, partly in section, of the grinder and cylinder block;

Fig. 3 is an end elevational view thereof 45 taken from the right hand end of Fig. 1;

Fig. 4 is an enlarged fragmentary cross sectional view illustrative of a detail of the valve grinder;

Fig. 5 is a perspective view of one of the 50 valve oscillating parts of the grinder; and

Fig. 6 is a top plan view of a valve showing means thereon for coöperation with the part shown in Fig. 5.

Referring to these drawings; the valve

grinder includes a movable frame and a part on which the frame is mounted for movement, such part being adapted to be removably secured in a convenient manner to the top of the cylinder block of an engine. As shown, the movable frame consists of a longitudinal bar 10 and legs 11 depending at right angles to such bar and arranged one at each end of the latter. The stationary part consists of a bar 12 which 60 parallels the bar 10 and is pivotally secured, as by pins 13, to the rearward lower ends of the legs 11.

To illustrate the application of the valve grinder, a cylinder block of an engine is 70 conventionally shown at A. As shown, block A has four cylinders c therein and the eight valves for these cylinders are arranged in a single row at one side of the cylinders. The studs, by means of which 75 the cylinder head is secured to the block A, are shown at s. The bar 12 is provided with openings to receive certain of these studs, or their equivalent as the cap screws which are sometimes used, and these holes are so 80 arranged that the bar 10 is disposed parallel with and directly above the row of valves v. When studs are used, as shown, the bar 12 is held to block A by nuts n, which however would not be necessary if 85 cap screws are used, as is sometimes the case. The legs 11 are preferably so pivoted to bar 12 that their lower ends 14 abut the top face of block A and hold bar 10 in parallelism therewith.

Loosely mounted in bar 10 are a series of vertical stems 15, one for each valve v and in axial alinement therewith. On the lower end of each stem 15 is a block 16, which as shown in Fig. 5, has in its lower 95 face a pair of spaced pins 17 to engage in a correspondingly spaced pair of holes h in the upper face of valve v. Thus each valve v may be turned on its axis by a turning of the stem 15 thereabove. Obviously, other 100 interengaging means may, if desired, be provided on block 16 and valve v to accomplish this function.

Fixed on the upper end of each stem 15 is a gear 18 and the several gears mesh with a 105 rack 19 which is slidably longitudinally on the bar 10. As shown in Fig. 4, bar 10 has an upstanding flange 20, against which the rear face of the rack abuts to hold it in proper meshing relation with the gears 18. 110

Guides 21, secured to flange 20 and bar 10, overlie the top of the rack and hold it from vertical displacement. Rack 19 is manually reciprocable by means of a lever 22, which is pivoted at 23 to a forwardly extending ear 24 of the bar 10 and this lever is connected to rack 19 by a link 25. The lever 22 thus swings in a horizontal plane parallel with the plane in which rack 19 is reciprocable and at right angles to the axes of the valve oscillating elements. The rack 19 is a narrow member and the securing bar 12 lies approximately beneath it when the axes of the valve oscillating spindles are in vertical position. The peripheries of the gears 18 also extend approximately to the vertical plane passing through the bar 12 so that the device is compact and legs 11 are easily held against the cylinder block by a slight downward pressure upon the lever 22, thus making it unnecessary to lock the carrier in position.

A guide 26 is supported from bar 10 in parallelism therewith by integral depending parts 27, which, limit the extent of movement of the lever and thus the extent of movement of rack 19. The movement of rack 19 is, however, sufficient to turn gears 18 through at least one full revolution. The guide 26 overlies lever 22 adjacent its connection with link 25 and lies substantially contiguous with the upper face of lever 22.

Consequently, the latter, aside from its function in rotating the stems 15, is adapted for use in raising or lowering bar 10 on its pivots 13. While the lever 22 could be used for this purpose without the guide 26, nevertheless, such use of the lever would place undesired strains on the pivot 23 or 40 the pivots of link 25. With the guide, such strains, and the binding action incident thereto, are avoided.

In order to force the blocks 16 toward the valves and to secure pressure on the latter during their oscillation or rotation, as the case may be, a spring 28 is coiled about each stem 15 and acts between the under face of bar 10 and head h (or by preference a washer 29 which is placed on stem 15 and 50 abuts head h) and acts against the under face of the bar to force the stems downwardly. The underfaces of gears 18, of course, limit this downward movement of the stems but the latter are of such length 55 that when the bar 10 is positioned, as in Figs. 2 and 3, the gears are lifted sufficiently from the bar to permit the springs 15 to freely act in the performance of their intended functions.

60 In operation, the bar 12 is secured to the cylinder block as described and the operator, performs the other usual preliminary operations necessary to valve grinding, such as the placing of springs k about the stems e 65 of valves v to lift the latter from their seats

when pressure is relieved. Grinding compound is applied in the usual way to the valves and then the operator swings frame 10, by means of lever 22 into the illustrated position. On oscillation of the lever, the projections 17 will automatically become engaged in the holes h . Then the grinding operation is performed by oscillating the lever 22 throughout the desired range. From time to time, the valves may be lifted 70 from their seats by raising lever 22, the springs k effecting this result as soon as the pressure of springs 28 is relieved by the lifting of bar 10. If the valves are to be shifted to a new angular position, this may be accomplished by swinging lever 22 while bar 10 is lifted, so that when the latter is depressed the valves will seat in a new position.

An important feature of the invention 85 consists in the arrangement, whereby the one lever serves conveniently as a means for oscillating the valves and for moving them, or permitting them to be moved, to and from their seats during the grinding operation. Thus, all the operator has to do is to swing the lever back and forth in one plane and from time to time swing it in another plane to move bar 10 on its pivots. Moreover, should the weight of bar 10 not be 90 sufficient to hold it in the illustrated position, a slight downward pressure on the lever 22, which, with the particular disposition of the lever, is more or less natural anyway, will hold the bar in the desired 95 position.

The invention has been disclosed herein, in an embodiment, at present preferred, for illustrative purposes but the scope of the invention is defined by the appended claims 105 rather than by the foregoing description.

What I claim is—

1. A valve grinder, comprising a member having means to support it from a cylinder block and in overlying relation to the valves 110 thereof, a second member adapted to be secured to said block and to which the first member is pivotally connected, so as to rotate about a horizontal axis, a plurality of valve-oscillating elements mounted in said first 115 member, and means for oscillating said elements, said means including a manually operable lever pivoted to the first member to swing in a plane at right angles to the axes of said valve-oscillating elements and adapted 120 for use in moving the first member relatively to the second member.

2. A valve grinder comprising a bar having two longitudinally spaced legs to support it from and in spaced relation with the 125 top face of a cylinder block, and adapted to directly engage said block, a second bar to which said first bar is pivoted so as to rotate about a horizontal axis and which is provided with means for attachment to the 130

cylinder block, so that the first bar is positioned parallel and in overlying relation with the valves, a plurality of valve-oscillating elements rotatably mounted in the first bar, and a lever mounted on the latter to simultaneously oscillate said elements, said lever moving in a plane at right angles to the axes of said valve-oscillating elements.

3. A valve grinder comprising a member 10 adapted to be supported in overlying relation with the valves of a cylinder block, a second member adapted to be secured to said block and having pivotal connections with said first member, so that said first member 15 is rotatable about a horizontal axis, a plurality of valve-oscillating elements mounted in said first member and each provided with a toothed wheel at its upper end, means comprising a horizontal lever for oscillating 20 said wheels, and means for securing said second member to said block and located approximately in line with said pivotal connections and the vertical plane passing through the peripheries of said toothed 25 wheels when their axes are in vertical position.

4. A valve grinder comprising a member adapted to be supported in overlying relation to the valves of a cylinder block, a second member adapted to be secured to said block and to which said first member is pivotally connected, so as to rotate about a horizontal axis, a plurality of valve-oscillating elements provided with gears located 35 above said first member, a lever secured to

said first member and movable in a plane at right angles to the axes of said gears, and a narrow rack engaging said gears and connected to said lever for oscillating said valve-oscillating elements, the pivotal connections with said second member being located substantially beneath said rack when the axes of said valve-oscillating members are in vertical position.

5. A valve grinder comprising a support- 45 ing member adapted to be supported in definite relation to a cylinder block, a securing bar pivoted to said member so that said member is rotatable about a horizontal axis and provided with means for securing it to 50 said cylinder block, a rack with vertical teeth sliding upon said supporting member, a plurality of valve-oscillating spindles rotatively mounted in said supporting member and movable both longitudinally and axially 55 relatively thereto, a gear upon the upper end of each of said spindles and adapted to bear on said supporting member, a spring on each of said spindles below said supporting member and engaging said member and its spindle so as to tend to hold said gear in engagement with said supporting member, each of 60 said spindles being movable against the action of its spring so as to disengage its gear from said rack, and a lever fulcrumed upon 65 said supporting member and moving in a plane at right angles to the axes of said spindles.

HARRY A. WRIGHT.
